United States Patent Office.

WILLIAM JOHNSTON, OF APPLETON, WISCONSIN.

Letters Patent No. 84,949, dated December 15, 1868.

IMPROVED BEDSTEAD-FASTENING.

The Schedule referred to in these Letters Patent and making part of the same.

To all whom it may concern:

Be it known that I, WILLIAM JOHNSTON, of Appleton, in the county of Outagamie, and State of Wisconsin, have invented a new and improved Bedstead-Fastening; and I do hereby declare that the following is a full, clear, and exact description thereof, which will enable those skilled in the art to make and use the same, reference being had to the accompanying drawings, forming part of this specification, in which—

Figure 1 is a side view of a part of a side-rail and post of a bedstead, to which my improved fastening has been attached.

Figure 2 is a detail sectional view of the post, showing one part of the fastener attached thereto.

Figure 3 is a detail side view of the end of the side-rail, showing the other part of the fastener attached thereto.

Similar letters of reference indicate corresponding parts.

My invention has for its object to furnish an improved bedstead-fastening, strong, durable, simple in construction, not liable to get out of order, and which may be easily attached and detached; and

It consists in the fastening constructed and operating as hereinafter more fully described.

A represents the post of the bedstead, and

B represents the side-rail, about the construction of which parts there is nothing new.

C is one part of the fastening, which is let into a recess formed in the post A to receive it, where it is secured in place by a pin, screw, or bolt, passing through said post and through a hole in said piece C.

c¹ is a lug, formed upon the lower part of the piece C, so as to leave a wedge-shaped recess upon the rear or inner side of said lug, as shown in figs. 1 and 2.

Upon the upper part of the piece C is formed a second lug, c², in such a way as to leave a space or channel upon its upper end and inner side, as shown in fig. 2.

D is the other part or piece of the fastening, which is made in about the shape of the letter D, and which is fitted into a recess formed in the inner side of the end of the rail in the usual manner.

The piece D is so arranged that its straight side may project beyond the end of the rail B, as shown in fig. 3.

Upon the lower part of the projecting part of the piece D is formed a lug, d¹, fitting into the recess in the rear of the lower lug c¹ of the piece C, as shown in dotted lines in fig. 1.

Upon the upper part of the projecting part of the piece D is formed a second lug, d², of such a form that it can enter the space or channel above and in the rear of the lug c² of the piece C, and rest against the rear side of said lug c², as shown in dotted lines in fig. 1.

In attaching the fastener, the lower lug d¹ of the piece D is entered in the space between the lugs c¹ and c² of the piece C, and the upper lug d² is entered in the space above the lug c².

Then, by pushing the piece D inward and downward, the lugs d¹ and d² pass into their places in the rear of the lugs c¹ and c², securely fastening the said parts or pieces together.

The fastener is unfastened by simply raising the piece D, the form of the channel or space in the rear of and above the lug c² causing the piece D, at the same time, to move outward.

I claim as new, and desire to secure by Letters Patent—

An improved bedstead-fastener, C c¹ c² D d¹ d², constructed and operating substantially in the manner herein shown and described.

WILLIAM JOHNSTON.
